UNITED STATES PATENT OFFICE.

THOMAS ALLSOP AND WALTER W. SIBSON, OF PHILADELPHIA, PENNSYLVANIA, ASSIGNORS
TO THE PHILADELPHIA DRYING MACHINERY COMPANY, OF PHILADELPHIA, PENNSYLVANIA, A CORPORATION OF PENNSYLVANIA.

DYEING APPARATUS.

No. 918,485.

Specification of Letters Patent. Patented April 13, 1909.

Application filed October 30, 1908. Serial No. 460,266.

To all whom it may concern:

Be it known that we, THOMAS ALLSOP and WALTER W. SIBSON, citizens of the United States, residing at Philadelphia, in the county of Philadelphia and State of Pennsylvania, have invented certain new and useful Improvements in Dyeing Apparatus; and we do hereby declare the following to be a full, clear, and exact description of the invention, such as will enable others skilled in the art to which it appertains to make and use the same.

This invention relates to improvements in dyeing machines of the open-vat type, and is particularly related to that form of machine illustrated, described and claimed in our pending application for Letters Patent of the United States, Serial No. 452,377, filed September 10, 1908.

20 The machine of the application referred to is primarily designed for the circulation of the dye-liquor within the vat during the dyeing operation, whereby a much more uniform dyeing of the material or articles 25 under treatment is accomplished than by those machines wherein the dye-liquor remains in a quiescent state. In the machine in question, however, the materials or articles have no movement while subjected to 30 the action of the dye-liquor, but remain at rest in the containing cage, the liquor being caused to pass through this cage.

The present invention has in contemplation the provision of a dyeing machine embodying the general principles of the machine covered by the application aforesaid, but combining therewith means whereby the goods or articles under treatment may be agitated or tumbled about to permit the 40 dye-liquor to permeate the mass, thus obtaining a machine having special advantages for dyeing hosiery.

The invention also aims to provide a machine capable of service either in dyeing or 45 washing the goods after the latter have been dyed, and in which provision is made for removal of the cylinder or drum containing the goods for transfer to another machine, without, however, disturbing the circulating 50 mechanism, or impairing the same in the least.

The invention further contemplates providing a machine of the class referred to having provision that enables the circulating

mechanism to be stopped in its operation 55 without affecting the operation of the cylinder or drum, and vice versa, so that should conditions require the same, the liquid within the vat can remain in a quiescent state while the cylinder or drum can continue to 60 rotate, or the cylinder or drum may be brought to rest while the circulation of the liquid continues.

With these general objects in view, and others that will appear as the nature of 65 the improvements is better understood, the invention consists substantially in the novel construction, combination and arrangement of parts hereinafter fully described, illustrated in the accompanying drawings, and 70 pointed out in the appended claims.

In the drawings—Figure 1 is an end elevation of a dyeing machine wherein the present invention is incorporated. Fig. 2 is a top plan view thereof. Fig. 3 is a front elevation of the machine.

Referring in detail to the drawings, the numeral 1 designates the vat of the machine. This may be formed of any suitable material, but is preferably rectangular in form, the 80 forward end of the vat being curved and sustained by a suitable support 2.

Within the vat 1, and adjacent to the curved end thereof, is a cylinder or drum 3, said cylinder having solid heads 4 at its ends, 85 which heads are provided with trunnions 5 through the medium of which the cylinder or drum 3 is journaled for rotation in said vat. To this end the sides of the vat are provided with upwardly extending notches 6, and surrounding each of said notches 6, at the exterior of the vat 1, is a bearing 7, the trunnions 5 being seated in these bearings. It is to be observed, however, that the bearings 7 are closed at their outer sides, so that longitudinal movement of the cylinder or drum 3 is prevented, and each of the bearings 7 is further provided with a pair of converging 90 guide surfaces 8 at its sides, whereby a flaring mouth is imparted to the bearing 7 at its upper end. By reason of this the trunnions 5 may be readily introduced to the bearings 7, said trunnions passing down the surfaces 8, and being guided by the latter into the bearing portions. It will thus be seen that 95 while the cylinder or drum is properly supported in the vat 1, the same is free to be removed therefrom, and to the accomplish-

100

105

ment of this end each of the heads 4 is provided with a radially extending hoisting standard 9 that is fixedly connected to the head; the outer end of said standard projecting beyond the perimeter of the head and having an opening 10 formed therein for the attachment of suitable hoisting mechanism. It will be understood that the standards 9 follow the heads 4 in the rotation of the cylinder or drum 3 to permit which the length of said standards is such as not to contact with either the bottom or the curved end of the vat.

The body portion of the cylinder or drum 3 may be of iron or wood suitably perforated for the admission of the dye-liquor, or the same may be of wire fabric, it being necessary that the construction shall be such as to permit the dye-liquor freely entering the cylinder or drum in order to permeate the mass of the material or articles being treated, and in order that access may be readily had to the interior of the cylinder or drum the latter is provided with a hinged door 11 through which, when the cylinder or drum has been properly positioned, the material or articles may be readily inserted and removed from the same.

The vat 1 is provided with an outlet 12, 30 and associated with said vat is a pipe 13 having branches 14 through the medium of which steam may be introduced to the dye-liquor within the vat.

That the cylinder or drum 3 may be properly rotated for the purpose of agitating the mass of material or articles therein, and thereby subjecting the same to uniform treatment by the dye-liquor, a spur gear 15 is fixedly connected to one of the heads 4, said 40 spur gear meshing with a spur gear 16 that is shiftably mounted upon a stub shaft 17, one end of said shaft being held by a bracket arm 18 fixed to the side of the vat 1, the other end of said shaft being arranged in a 45 supporting bracket 19 carried by a supporting plate 20 that, in turn, is carried by the vat 1. The hub of the gear 16 is provided with a loose collar 21 having oppositely-projecting pins 22 at its sides, and said pins are 50 received by elongated slots 23 formed in the sides of a loop 24 that is included as a part of a shifting lever 25. This lever is pivoted at its lower end, as at 26, to the side of the vat, and it will thus be seen that when pressure is applied to the upper end of the lever 25 the gear 16 may be shifted into and out of engagement with the spur gear 15. The shiftable gear 16 also meshes with an idler pinion 27 that is mounted upon a shaft 28 60 carried by the supporting bracket 19, and this idler pinion engages a power gear 29 carried at one end of a power shaft 30 that is journaled in a bearing 31 arranged in the supporting bracket 19, the other end of the shaft 65 30 being likewise journaled in a suitable bearing 32 arranged upon the supporting plate 20.

A sprocket wheel, or other suitable form of transmitting gear, 33, is also carried by the power shaft 30, adjacent to the spur gear 29, and through the medium of this sprocket wheel power from any suitable source is applied to the shaft 30. Hence, when the shaft 30 is rotating, and the gear 16 engages the spur gear 15 and the idler pinion 27, the cylinder or drum 3 will rotate under the influence of said shaft 30, but movement of said cylinder or drum is controlled essentially by the shiftable gear 16.

Like the machine disclosed in our pending application Serial No. 452,377, aforesaid, the present machine has provisions for freely circulating the dye-liquor. For this purpose the vat 1 has located in the end thereof opposite to the end wherein the cylinder or drum 3 is journaled a pair of transversely-extending partitions 34. These partitions extend across the entire width of the vat 1, and are spaced from each other to provide a compartment 35, but it will be observed that the upper and lower edges of said partitions terminate at points removed from the top and bottom of the vat 1, so that spaces remain at the top and bottom of the compartment 35, whereby the dye-liquor may readily pass over and under said compartment. 95 The upper and lower ends of the compartment 35 are closed by valves 36 and 37, and these valves are in the form of doors that are pivoted at their outer edges to the upper and lower edges of the outer partition 34. When, therefore, the valves 36 and 37 swing open and shut the free edges of the same are directed toward the cylinder or drum 3. The valves 36 and 37 control the direction of circulation of the dye-liquor, and the relative movement of the valves is such that when one is closed the other is opened. Thus it will be seen, as clearly illustrated in Fig. 1, the valve 36 is in closed position, while the valve 37 is open, and the dye-liquor, in circulating through the compartment 35, will be discharged at the bottom thereof, while this discharge will occur at the top of said compartment when the position of the valves is reversed to that illustrated in Fig. 1. The arrangement described provides for discharge of the dye-liquor from the compartment 35 either to the top or to the bottom of the vat 1, and thus to either the central portion of the cylinder or drum 3, or to the lower edge thereof. In this connection, a deflector plate 38 is arranged at the lower edge of the inner partition 34, which plate extends towards the bottom edge of the cylinder or drum 3, so that a passage is formed between said plate and the bottom of the vat to insure circulation of the dye-liquor along said bottom to the extreme lower edge of the cylinder or drum. 110

That the dye-liquor may freely enter the compartment 35 the outer partition 34 is provided with an opening or openings 39, said partition being sufficiently removed 5 from the adjacent end of the tank to provide a circulating passage or space of substantial size, and the dye-liquor entering this space readily passes into the compartment 35 through said opening or openings 35. 10 As in the previous machine, provision is made herein for effecting circulation of the dye-liquor to the required extent, and for this purpose propeller wheels 40 are arranged in the compartment 35. It is preferable that a plurality of these wheels be employed, and the same are arranged opposite the openings 39, so that as said wheels rotate they suck the dye-liquor through said openings into said compartment. The construction of the wheels 40 is precisely the same as that disclosed in our application previously referred to, and it is therefore unnecessary to enter into a detailed description thereof; suffice it to say that as the dye-25 liquor is drawn in through the openings 39 the same will be deflected outwardly from the hubs of the wheels 40 and discharged at the outer edges thereof. Each of the wheels 40 is driven from a vertically disposed shaft 30, 41, journaled in suitable bearings, a pair of bevel gears 42 being employed to couple each wheel 40 with its shaft 41, and said shafts 41 are driven from oppositely-arranged bevel gears 43 that engage similar 35 gears 44, the latter being arranged at the upper ends of the shafts 41. By arranging the gears 43 opposite to each other, or with their teeth reversely disposed, the wheels 40 will rotate in opposite directions, that is, one 40 of the wheels will rotate toward the right, while the direction of rotation of the other wheel will be to the left, and this insures uniform distribution of the dye-liquor as the latter is projected from the compartment 35 45 into the vat 1.

The wheels 43 are fixedly connected to a tubular shaft 45 that is mounted upon the power shaft 30, and free to rotate thereon, but it is intended that the shaft 45 shall derive 50 its motion from the power shaft 30, to which end a clutch collar 46 is splined to the shaft 30, being shiftable therealong through the medium of a hand lever 47, said collar 46 engaging a clutch face at the contiguous end of 55 the tubular shaft 45, and thus locking the latter into engagement with the shaft 30.

The present machine also embodies means for reversing periodically and automatically the direction of flow of the dye-liquor, as the latter circulates in the vat 1, and this is accomplished by alternately opening and closing the valves 36 and 37, these valves moving in unison by means of a connecting rod 48 that is suitably pivoted to both of the valves 65 36 and 37, in a manner similar to that illus-

trated and described in our aforesaid application.

Mounted in bearing standards 49, carried by the supporting plate 20, is a cam shaft 50 that extends transversely of the vat, and this shaft is provided adjacent to each of its ends with a cam 51. Associated with the cams 51 are links 52 the lower ends of which are pivotally connected to the upper valve 36, as at 53. Upon the upper end of each of the links 52 is a pair of bearing rolls 54 that are arranged at opposite sides of the contiguous cam and work upon the face of the latter, so that in the rotation of said cams the links 52 are caused to rise and fall, and thereby open 58 and close the valve 36, the valve 37 operating in connection therewith through the medium of the rod 48. The upper end of each of the links 52 is provided with an elongated slot 55, said slots receiving the shaft 50, and thus permitting free movement of the links upon said shaft, and said links pass through the supporting plate 20, suitable openings being pierced therein for this purpose. The arrangement of the links 52, the cams 51, and cam shaft 50 is precisely the same as in our former application, and, as is also true of the construction disclosed in said application, the cam shaft 50 is operated by a bevel gear 56 carried thereby, said gear meshing with a horizontally disposed bevel gear wheel 57 associated with a worm wheel 58 journaled upon a suitable support. This worm wheel 58 meshes with a worm 59, in the form of a sleeve, said worm being loosely mounted 100 upon the tubular shaft 45, and said worm has at one of its ends a clutch face adapted to be engaged by a clutch collar 60 splined upon the shaft 45 and operated thereon by a manually-controlled shifting lever 61. If, therefore, it be desired at any time to stop reversal of the circulation of the dye-liquor, it is but necessary to disconnect the collar 60 from the worm 59, whereupon the cam shaft 50 ceases to operate, and movement of the valves 110 36 and 37 is thereby stopped, and should it be desired to discontinue circulation of the dye-liquor, so that the latter may remain in a quiescent state, this also may be accomplished by merely disconnecting the clutch collar 46 115 from the shaft 45, whereupon the propeller wheels 40 will cease their rotation.

In operating the herein described machine the requisite dye-liquor is introduced to the vat 1, and the cylinder or drum 3 having been 120 provided with the material or articles to be dyed, said cylinder or drum is introduced to the vat 1, if it has not previously been placed therein, the trunnions 5 entering the bearings 7 as hereinbefore described. If the gear 125 16 is in mesh with the gears 15 and 27, and the clutch collars 46 and 60 engaged with their respective elements, motion being imparted to the shaft 30 will cause the cylinder or drum 3, the propeller wheels 40, and 130

the valves 36 and 37 to operate. With the valve 37 open, as disclosed in Fig. 1, the dye-liquor is discharged by the wheels 40 through the bottom of the compartment 35, and passes along the bottom of the vat 1 beneath the deflector plate 38, and is discharged against the bottom portion of the cylinder or drum, 3, a portion, however, following the curved end of the vat 1 around the periphery of the cylinder or drum. The dye-liquor is thus caused to pass through the cylinder or drum in rising from the bottom of the vat, and permeates the mass within the cylinder or drum, being drawn therefrom, and passing over the valve 36, when the latter is closed, as shown in Fig. 1, said dye-liquor passing down between the outer partition 34 and the end of the vat 1, and again entering the compartment 35 through the openings 39. This direction of the circulation continues until the valve 37 is closed, and the valve 36 opened, through the action of the cams 51 and the links 52, whereupon the direction of flow of the dye-liquor is reversed, the same passing out through the top of the compartment 35 and entering the cylinder or drum at substantially its middle portion, or at a point substantially mid-way the upper and lower edges thereof, whence the dye-liquor permeates the mass and leaves the cylinder or drum at its bottom and opposite side portions, and from these points the dye-liquor is drawn along the curved end and bottom of the vat, beneath the deflector plate 38 and valve 37, which is now closed, and rises in the space between the outer partition 34 and the end of the vat, and thence enters the compartment 35 from which it is again discharged through its top, if the valve 36 still be open. This automatic reversal of the direction of flow of the dye-liquor will continue so long as the cam shaft 50 is geared with the shaft 45, but if it be desired to circulate the liquor in but one direction, determined by closing either the valve 36 or the valve 37, the clutch collar 60 is disengaged from the worm 59, whereupon the dye-liquor will follow the path of discharge from the compartment 35 in accordance with the open position of either of the valves 36 or 37. If it be desired to stop rotation of the propeller wheels 40, as is sometimes desirable when the machine is employed for washing the materials or articles after the same are dyed, this may be accomplished by disengaging the clutch collar 46 from the sleeve 45, in which event, the shaft 30 continuing to operate, the cylinder or drum 3 will continue to revolve and tumble the goods around in the wash water. As before stated, the gear 16 may be readily shifted upon its shaft, and when the same is disengaged from the spur gear 15, the cylinder or drum 3 may be readily removed from the vat 1 for transfer to another machine, or

for removing the goods therefrom, without disturbing the circulating mechanism, or impairing the same in the least.

The herein-described machine is capable of use either for dyeing or for washing, and by its employment affords the advantage of obtaining in a single machine both the rotation of the material or articles being treated within the dye-liquor, and uniform circulation of the latter with respect to such material or articles. Furthermore, the machine possesses the advantage of dyeing or washing the material or articles while the dye-liquor or wash-water is either circulated or in a quiescent state, and adapts the machine to numerous uses where a non-revolving container for the material or articles cannot be adapted.

The machine is of especial advantage in the softening of the goods, such as stockings, after the latter have been dyed and washed. Ordinarily, in this softening operation, the agitation of the soapy solution causes a deposit of small particles of a curdy nature on the outside layers of the goods. With the present machine, however, it is possible to soften the stockings by merely causing the cylinder or drum to revolve and thereby tumble the goods around in the soapy solution, the propellers not revolving but remaining at rest, and, consequently, the soap will not be churned up into curds. The stockings, therefore, will emerge from the machine soft and delicate to the touch, and free from the curdy deposits mentioned.

Having thus described the invention, what is claimed as new, and desired to be secured by Letters Patent, is:

1. In a dyeing apparatus, a vat, a rotatable perforated cylinder arranged therein, means within the vat for circulating the dye-liquor therein, and means for actuating said circulating means and said cylinder simultaneously or independently of each other.

2. In a dyeing apparatus, a vat, a rotatable perforated cylinder arranged therein, means within the vat for circulating the dye-liquor therein, means associated with said circulating means for changing the direction of the flow of the dye-liquor in its circulation, means for driving said circulating means, connections between said driving means and said circulation-changing means whereby to impart to the dye-liquor alternate flow in reverse directions or in but one direction, and means co-operating with said driving means to operate the circulating means and the cylinder simultaneously or independently of each other.

3. In a dyeing apparatus, a vat, a rotatable perforated cylinder arranged therein, means within the vat for circulating the dye-liquor therein, and means associated with said circulating means for causing circulation

of the dye-liquor alternately in reverse directions and maintaining the flow in such directions for determinate periods.

4. In a dyeing apparatus, a vat, a rotatable perforated cylinder arranged therein, devices within the vat for circulating the dye-liquor therein, means for actuating said devices, means associated with said circulating devices for changing the direction of the flow 10 of the dye-liquor in its circulation, and means for actuating said circulation changing means by the actuating means for the circulating devices.

5. In a dyeing apparatus, a vat, a rotatable perforated cylinder arranged therein, means within the vat for circulating the dye-liquor therein, means for actuating said circulating means, and connections between 15 said actuating means and said cylinder for rotating the latter by said actuating means.

6. In a dyeing apparatus, a vat, a rotatable perforated cylinder arranged therein, means within the vat for circulating the dye-liquor therein, means for actuating said 20 circulating means, connections between said actuating means and said cylinder for rotating the latter by said actuating means, and a movable coupling element included in said 25 connections for engaging and disengaging the rotatable cylinder with and from said actuating means.

7. In a dyeing apparatus, a vat, a rotatable perforated cylinder arranged therein, means within the vat for circulating the dye- 30 liquor therein, means for actuating said circulating means, a train of gears between said actuating means and said cylinder for rotating the latter by said actuating means, and a shiftable gear included in said train, whereby 40 to engage and disengage the cylinder with and from said actuating means.

8. In a dyeing apparatus, a vat, a rotatable perforated cylinder removably mounted within said vat, means within the vat for circulating the dye-liquor therein, means for 45 actuating said circulating means, a train of gears between said actuating means and said cylinder for rotating the latter by said actuating means, and a shiftable gear included in 50 said train, whereby to engage and disengage the cylinder with and from said actuating means.

9. In a dyeing apparatus, a vat, a rotatable perforated cylinder arranged therein, means within the vat for circulating the dye- 55 liquor therein, a shaft geared to said circulating means for actuating the latter, a train of gears between said actuating shaft and said cylinder for rotating the latter by said shaft, 60 and a shiftable gear included in said train, whereby to engage and disengage the cylinder with and from said actuating means.

10. In a dyeing apparatus, a vat, a rotatable perforated cylinder arranged therein, means within the vat for circulating the dye- 65 liquor therein, a driving shaft, a tubular shaft mounted upon said driving shaft and geared to said circulating means for actuating the latter, means for coupling said tubular shaft with said driving shaft, means associated with said circulating means for changing the direction of the flow of the dye-liquor in its circulation, connections between said tubular shaft and the circulation-changing means for actuating the latter by said tubular shaft, and connections between said driving shaft and said cylinder for actuating the latter by the driving shaft.

11. In a dyeing apparatus, a vat, a rotatable perforated cylinder arranged therein, 80 means within the vat for circulating the dye- liquor therein, a driving shaft, a tubular shaft mounted upon said driving shaft and geared to said circulating means for actuating the latter, means for coupling said tubular shaft with said driving shaft, means associated with said circulating means for changing the direction of the flow of the dye-liquor in its circulation, a shaft connected to said 85 circulation-changing means for actuating the same, connections between the tubular shaft and the last-mentioned shaft for actuating the latter from said tubular shaft, and connections between said driving shaft and said cylinder for actuating the latter by the driving shaft.

12. In a dyeing apparatus, a vat, a rotatable perforated cylinder arranged therein, means within the vat for circulating the dye-liquor therein, and a deflector plate arranged 100 substantially parallel with the bottom of the vat and extending from said circulating means toward said rotatable cylinder to maintain circulation of the dye-liquor in a substantially fixed path.

13. In a dyeing apparatus, a vat, a rotatable perforated cylinder arranged therein, means within the vat for circulating the dye-liquor therein, means associated with said circulating means for reversing the direction 110 of the flow of the dye-liquor in its circulation, and a deflector plate arranged substantially parallel with the bottom of the vat and extending from said circulating means toward said rotatable cylinder to maintain circulation of the dye-liquor in a substantially fixed path.

In testimony whereof we affix our signatures, in the presence of two witnesses.

THOMAS ALLSOP.
WALTER W. SIBSON.
